COMBINED BOTTLE WARMER AND STORAGE UNIT

Richard N. Lane, Phoenix, Ariz.

Application December 24, 1956, Serial No. 44,316

Term of patent 14 years

(Cl. D81—10)

Fig. 1 is a perspective view of a combined bottle warmer and storage unit showing my new design;

Fig. 2 is a top plan view on a slightly reduced scale;

Fig. 3 is a right side elevational view of Fig. 2;

Fig. 4 is a front elevational view of Fig. 2; and

Fig. 5 is a rear elevational view of Fig. 2.

I claim:

The ornamental design for a combined bottle warmer and storage unit, substantially as shown.
